(57) **CLAIM**

The ornamental design for a laundry appliance, as shown and described.

DESCRIPTION

FIG. 1 is a right front perspective view of the design of the laundry appliance;

FIG. 2 is a front elevational view thereof;

FIG. 3 is a right side elevational view with the left side being a mirror image thereof; and,

FIG. 4 is a top plan view thereof.

The broken line showing of the appliance top and sides, front dial, lower front panel, upper left and right panels in FIGS. 1-4 is included for the purpose of illustrating portions of the laundry appliance and forms no part of the claimed design.

1 Claim, 4 Drawing Sheets
